UNITED STATES PATENT OFFICE.

WILLIAM H. TILLOU, OF LEROY, NEW YORK.

COMBINED CULTIVATOR AND HARROW.

No. 800,514.

Specification of Letters Patent.

Patented Sept. 26, 1905.

Application filed September 1, 1904. Serial No. 223,027.

To all whom it may concern:

Be it known that I, WILLIAM H. TILLOU, of Leroy, in the county of Genesee and State of New York, have invented a new and useful Improvement in a Combined Cultivator and Harrow, which improvement is fully set forth in the following specification and shown in the accompanying drawings.

My invention is a combined cultivator and harrow, the same being hereinafter fully described, and more particularly pointed out in the appended claims.

The objects and advantages of the invention will be brought out and made to appear in the following specification, reference being had to the accompanying drawings, which, with the reference characters marked thereon, form a part thereof.

Figure 1 is a plan of my improved cultivator and harrow, parts being shown in various positions by full and by dotted lines. Fig. 2 is a rear elevation of the same. Fig. 3 is a plan of a pivotal or swinging axle detached. Fig. 4 is an edge view of the axle seen as indicated by arrow 4 in Fig. 3. Fig. 5 is a view of the axle seen as indicated by arrow 5 in Fig. 3. Fig. 6 is an end elevation of the combined machine seen as indicated by arrow 7 in Fig. 1, parts being shown in various positions by full and dotted lines. Fig. 7 is a side elevation of the middle bar for holding the ends of the tooth-shafts, the frame and the shafts being in vertical transverse section near the bar.

Figs. 3, 5, and 7 are drawn to various scales larger than that of Figs. 1, 2, and 6.

A in the drawings is the frame of the machine; BB, the carrying-wheels; C, the draft-tongue, and D the driver's seat.

$k k' k'' k'''$, Figs. 1 and 2, are four horizontal tubular shafts or sections of shafts for holding a series of spring-teeth H for cultivating or for harrowing, the shafts being held at their outer ends in cup-shape bearings a , Figs. 2 and 6, pending beneath and secured to the frame A. These shaft-sections are coaxial in pairs, the sections $k k'$ together forming a forward divided shaft reaching from side to side of the frame and the sections $k'' k'''$ forming a similar rear shaft, the inner adjacent ends of the several sections being held in cup-bearings b , Figs. 1, 2, and 7, secured on opposite sides of a middle cross-bar d , carried by the front and the rear timbers of the frame A. The sections of the shafts pierce intermediate cross-timbers E E of the frame

A, in which timbers they have bearings, the inner ends of all the sections abutting against the opposing surfaces of the middle bar d .

The tubular shaft-sections $k k' k'' k'''$ are 60 formed with longitudinal slots c , Fig. 2, through which to insert the heads of T-shape bolts e for holding the spring-teeth H to place on the sections, the slots c being elongated to admit of lateral adjustments of the teeth. 65 By slightly turning the shaft-sections in their bearings $a b$ one way or the other the teeth will be pressed into the ground or raised therefrom, as the case may be. For the purpose of turning the shafts hand-levers $F F'$, 70 Figs. 1, 2, and 6, are provided, secured to the respective front sections $k k'$ of the shaft by clamping-plates. To cause the rear shaft-sections $k'' k'''$ also to turn with the forward sections, they are provided with arms $i l$, respectively, connected with the respective hand-levers $F F'$ by link-bars $m n$. Thus connected, each hand-lever serves to simultaneously turn both shaft-sections at the right or the 75 left of the middle bar d .

The hand-levers $F F'$ operate in combination with curved toothed racks $g g$, secured to the respective cross-timbers E E of the frame A, these toothed racks being concentric with the shaft-sections $k k'$, respectively. The 85 hand-levers are provided with spring-controlled pawls $h h'$ of common construction for engaging the teeth of the racks, said levers and the pawls being in convenient reach of the driver occupying the seat D. On account 90 of the shaft-sections $k k'$ and $k'' k'''$ at the two sides of the machine being independent of each other the spring-teeth H at either side of the machine may be lifted or depressed independent of those at the other side, using the hand-levers, as desired, this being frequently necessary, as when passing obstructions on one side or the other of the center line of the machine or for other purposes, and by moving both hand-levers alike, forward or backward, 100 all the teeth of the machine may be either lifted clear of the ground, as indicated by full lines in Fig. 6, or depressed to work the ground, as indicated by the dotted lines in the figure, the teeth being lifted, as shown, when 105 the machine is being moved from place to place without operating.

The plants or vegetation—as beans, for example—to be cultivated are in parallel rows commonly put in by a drill, three rows being 110 planted at a time. These rows are frequently more or less devious or crooked, and in cul-

tivating much difficulty is frequently experienced in endeavoring to cultivate sufficiently close to the rows or the hills to remove the weeds and still avoid disturbing the plants 5 where abrupt bends occur in the rows. To overcome this difficulty, provision is made for slightly swinging the carrying-wheels B B one way or the other independent of the frame A to cause the cultivator to swerve toward the right or the left as the crooking of 10 the rows may require. The axles $p p$, Figs. 1 to 5 and 6, for the wheels are not rigid with the frame A, but are held upon vertical pivot-bolts $o o$, so as to turn in horizontal directions on the frame, causing the wheels to assume different positions in vertical planes, as indicated in Fig. 1. Against the rear side of the frame A is placed an elongated toothed body or rack r , Figs. 1, 2, and 6, held to the 15 frame by some ordinary means, so as to have short longitudinal motions on its bearings. As shown, this toothed rack r is formed with horizontal slots $s s$, Fig. 2, bolts $t t$, occupying the slots and entering the frame, serving to 20 hold it in place; but the particular manner of securing the rack to the frame is not essential to my invention, the aim being to secure the rack so that it may have free longitudinal motions to the right or to the left on its bearing on the frame. Above the rack r is a 25 toothed segment u , Figs. 1, 2, and 6, held to turn in a vertical plane on a pivot-bolt v , projecting horizontally from a rigid standard w , rising from the frame A, the teeth of the 30 segment engaging with the teeth of the rack r , as shown. Rigid with the segment u is a short bar x , adapted to rock in a vertical plane on the bolt v , the two equal ends of the bar being provided with foot-rests or stirrups $y y$ for 35 the feet of the driver occupying the seat D. To the axles $p p$, carrying the wheels B B, are secured bent arms $z z$, Figs. 1 to 5 and 6, extending rearwardly from the frame A, connecting-bars $b' b'$ being joined pivotally to the 40 projecting ends of the arms, respectively, and to the ends of the toothed rack r in flexible joints $c' c'$, Fig. 2. From this it will be understood that if the driver by pressing downward against either stirrup y with his foot 45 tilt the rocking bar x one way or the other the two axles $p p$ will be simultaneously correspondingly turned on their bearings $o o$ and so cant the carrying-wheels B B or swing them to oblique positions one way or the 50 other, as appears in Fig. 1. The connections of the parts are such that in every case both wheels must turn or swing alike and in the same direction, which canting of the wheels will cause the cultivator to run obliquely toward the right or the left, as the case may be, 55 and so follow the sinuous rows independent of the team and without reining it from its course.

The cultivator is designed to cultivate and 60 complete three rows of plants at a time, the

intermediate row passing under the middle line of the cultivator represented by the dot-and-dash line d' , with the two extreme teeth at either side outside of the two outer rows. When using the machine as a cultivator, the 70 middle tooth, normally held at the inner end of the shaft-section k , is removed, and the driver upon the seat looking downward through the frame A at the middle row may readily see the crooks or irregularities therein 75 and so know when and in which direction to swerve the cultivator by pressing one or the other of the stirrups y with his foot, as stated. The middle bar d , holding the inner ends of the various shafts for carrying the teeth, is 80 preferably curved or offset, as shown, though this is not wholly essential to the invention. Besides holding the ends of the shafts this bar d carries a downwardly-projecting arm or pointer i' , Figs. 1, 2, and 6, the lower end of 85 which serves to indicate the position of the cultivator with reference to the middle row being cultivated, the attendant occupying the seat D, controlling the cultivator to keep the end of the pointer as nearly as possible directly over said row.

In addition to furrowing the ground near to the rows of plants it is also desirable to, in some cases, provide for the cultivator parts or elements to brush over or abrade the ground 95 in close proximity to the plants for the purpose of breaking over and killing small weeds that escape the teeth of the cultivator. Such parts are shown at I.

When the implement is used as a harrow, 100 the fingers I and the pointer i' are omitted, the middle spring-tooth being replaced on the inner end of the shaft-section k , Fig. 1, this tooth being removed when the machine is used as a cultivator to be out of the way of the 105 middle row being cultivated.

What I claim as my invention, and desire to 110 secure by Letters Patent, is—

1. A frame, carrying-wheels therefor, axles for said wheels mounted on vertical pivots, a bar at the middle of the frame and adapted to serve as an indicator for the steering of the device, bent arms secured to said axles, a connecting-bar pivotally joined to said arms, a toothed rack connected by flexible joints with 115 said bar, a rocking bar, a segment engaging said rack, and connected rigidly with said rocking bar to rock the bar in a vertical plane and stirrups connected with opposite ends of said bar. 120

2. A frame having slots for the passage of bent arms, carrying-wheels for said frame, axles for said wheels mounted on vertical pivots, a bar at the middle of the frame and adapted to serve as an indicator for the steering of the device, bent arms secured to said axles and passed through said slots, a rack connected by flexible joints with a bar, said bar pivotally connecting said arms, said rack being mounted for longitudinal movement on 125 130

the said frame within fixed limits, a segment engaging said rack, a rocking bar rigid with said segment to rock in a vertical plane, and stirrups connected with the opposite ends of 5 said bar.

3. A frame, carrying-wheels for said frame, a middle bar on the frame serving as an indicator for the steering of the device, axles for the carrying-wheels mounted on pivot-10 bearings on said frame, and means for turning said axles on their bearings.

4. A frame, carrying-wheels therefor, axles for said wheels mounted on vertical pivots, a middle bar adapted to serve as an indicator

for the steering of the machine, bent arms, 15 connected to said axles, a bar pivotally joined to said arms, a toothed rack flexibly connected with said bar, a rocking device, a segment rigid with said rocking device engaging the rack, and stirrups at the ends of said 20 rocking device.

In witness whereof I have hereunto set my hand, this 27th day of August, 1904, in the presence of two subscribing witnesses.

WILLIAM H. TILLOU.
